LADY'S OVERTSHOE

Robert Alpert, Malone, N. Y., assignor to Alba
Footwear, Inc., Malone, N. Y., a corporation of
New York

Application August 21, 1950, Serial No. 11,869

Term of patent 14 years

(Cl. D7—4)

To all whom it may concern:

Be it known that I, Robert Alpert, a citizen of the United States, residing at Malone, in the county of Franklin and State of New York, have invented a new, original, and ornamental Design for a Lady's Overshoe, of which the following is a specification, reference being had to the accompanying drawing, forming a part thereof, in which—

Fig. 1 is a perspective view of a lady's overshoe, showing my new design; and

Fig. 2 is a rear elevational view.

I claim:

The ornamental design for a lady's overshoe, as shown.

ROBERT ALPERT.
